LOCK NUT

Irving Richardson, Newark, N. J.

Application April 14, 1943, Serial No. 482,953

9 Claims.

(Cl. 151—7)

The present invention relates to lock nuts of the type in which a cushion member made a unitary part of the nut assembly, serves to take up looseness or vibration in use.

It is among the objects of the invention to provide a nut of the above type of simple and durable construction, which may be fabricated expeditiously and at small expense, and in which the application upon a bolt occurs without the likelihood of severing or loosening the washer from the body of the nut, so that the cushion takes a sharp thread impression of the bolt and the nut is thoroughly satisfactory in use.

In the accompanying drawing in which is shown one of various possible embodiments of the several features of the invention,

Fig. 1 is a plan view of the nut blank,

Fig. 2 is a sectional view taken on line 2—2 of Fig. 1,

Fig. 3 is a plan view of the nut blank after indentation of its rim,

Fig. 4 is a sectional view taken on line 4—4 of Fig. 3 and showing in dash lines the tool for making the indentations,

Fig. 5 is a fragmentary outer plan view on an enlarged scale of the indented rim shown in Fig. 4,

Fig. 6 is a fragmentary perspective of said rim as viewed from the inside,

Fig. 7 is a plan view of the completed nut,

Fig. 8 is a sectional view taken on line 8—8 of Fig. 7 showing in dash lines the tool for completing the nut assembly,

Fig. 9 is a perspective view of a fragment of the cushion washer as it appears after taking apart the assembled lock nut, and,

Fig. 10 is a view similar to Fig. 8 showing the nut as installed for use.

The nut blank 10 has a coaxial cylindrical socket 11 at one end protruding from one face thereof, the wall of which is considerably thinner than is the thick polygonal stock of the tapped body of the nut. Both the flat bottom 12 of the socket and its cylindrical inner wall 11 are devoid of indentations, keys or ribs. The rim of the socket is beveled at 13 to a relatively thin sharp edge 14.

The cushion member 15 is desirably of the vulcanized fiber, usually employed for such purpose. It fits in the socket, has a bore 16 somewhat smaller than the inner thread diameter of the nut and has a thickness such as to extend substantially to the level of the thick base 17 of the beveled rim 13 thereof.

According to the invention, the beveled rim 13

is forced inward and indented with a crown of equidistant sharply defined depressions 18, desirably wedge-shaped as shown, the apex of each indentation being near the base of the bevel, said depressions diverging outward to the sharp edge of the rim. The intervening unindented outer face of the rim thus presents a series of flat triangular teeth 19 connected at their lateral edges by the walls of the intervening depressed wedge-shaped teeth. The inner face of the inturned rim of course is not as sharply defined as is the outer indented face. The inner face is serrated in form as shown at 20 and desirably the troughs of the serrated conformation are interrupted solely at the inner edge to form sharp corners 21 thereat, the main body of the indented rim being continuous and uninterrupted.

The conformation above set forth and shown in Figs. 3 to 6, is readily imparted to the beveled rim shown in Fig. 2 by a single blow struck by a punch 23 shown in dash lines in Fig. 4 and which has a crown of radiating uniform triangular teeth 24. The punch teeth produce the sharp triangular or wedge-shaped indentations 18 in the beveled face 13 of the rim, leaving the triangular teeth 19 therebetween as best shown in Fig. 5. Substantially plane surfaces are thereby formed that converge from the sides of said triangles 18 and meet to form depressed hollow wedge shaped teeth that are widest at the inner periphery of the rim. By reason of the inclination of said bevel 13, the punch forces the rim radially inward to some extent as appears best from comparison of Figs. 2 and 4. The punch as it presses against the thin edge 14 of the beveled rim 13 effects severing of the inner periphery of said rim to form the corners 21, but the body of the beveled rim 13 beyond said sharp edge 14 is sufficiently strong to take the sharp impression of the punch without rupture.

As shown in Fig. 4, the indented crown conformed as set forth, extends over but is still substantially free from engagement with the cushion 15, which preferably is introduced into the socket before the punching operation set forth, but may, if desired, be introduced after such punching operation.

The indented rim of the socket is thereupon rolled inward to become embedded in the washer. Such rolling is preferably effected by a rolling tool 25 which presents the appropriate annular rolling conformation 26 so that by a single thrust thereon, the previously indented rim is pressed inward over the washer, thereby to cause the inner face of said rim to compress the washer

at the troughs of the serrated conformation 20, said troughs constituting rounded hollow teeth unitary at their lateral edges with those of the intervening triangular teeth 19 so that said hollow teeth have ample stiffness by reason of their truss-like arrangement to take the assembly thrust without collapse. The thrust of rolling tool 25 effects a flattening of the crests of the serrated edge upon the cushion, as appears from Fig. 7, as the stiffened troughs of said serrated rim are forced downward to bite against the washer 15 and to crenelate it as shown at 28 in Fig. 9. The thrust of the tool 25 also causes the sharp serrated inner periphery of the rim and the sharp corners 21 to bite into the face 15 of the washer as shown at 29.

By reason of the deformation of the cushion which results from forcing the troughs of the serrated rim of the socket thereinto, an annular welt 30 is raised from the cushion in intimate contact with the sharp crest edge of the serrated rim that encompasses it. The effective thickness of the cushion is thus increased for enhanced locking effectiveness upon the bolt.

As a result of the foregoing assembling operation, the cushion is securely, uniformly and positively locked into the nut, so that there is no possibility of either longitudinal or rotary displacement thereof under the stress of application to the bolt or of vibration or shock in use.

The gripping effectiveness of the socket with respect to the cushion member is uniformly distributed about the periphery of the latter, so that there is avoided the local distortion or displacement or complete loosening of the cushion that might be incurred in use if relatively large segments of the washer be left unclamped at points between their ends or if the cushion be not adequately locked in place.

As shown in Fig. 10 when the nut is screwed upon a bolt 31 the thread of the latter impresses its contour into the bore of the cushion as at 32 and the latter acts in the well understood manner to retain the nut from loosening.

As many changes could be made in the above article and method, and many apparently widely different embodiments of this invention could be made without departing from the scope of the claims, it is intended that all matter contained in the above description or shown in the accompanying drawing shall be interpreted as illustrative and not in a limiting sense.

Having thus described my invention, what I claim as new and desire to secure by Letters Patent of the United States is:

1. A lock nut blank having a coaxial cylindrical socket protruding from one face thereof, the rim of said socket having a sequence of substantially flat triangular teeth with the apices thereof near the inner periphery of said rim, and substantially plane surfaces converging from the sides of said triangles and meeting to form intervening depressed hollow wedge-shaped teeth that are widest at the inner periphery of said rim.

2. A lock nut comprising a nut blank having a coaxial cylindrical socket protruding from one face thereof presenting a beveled rim, a cushion washer in said socket, said rim extending inward over said washer, and having an uninterrupted serrated conformation at its inner face, with the troughs thereof indenting the face of said cushion, said serrated conformation comprising a sequence of substantially flat triangular teeth with their apices near the inner periphery of

said rim, substantially plane surfaces converging from the sides of said triangles and meeting to form intervening depressed hollow wedge-shaped teeth that are widest at the inner periphery of said rim.

3. A lock nut comprising a nut blank having a coaxial cylindrical socket protruding from one face thereof presenting a beveled rim, a cushion washer in said socket, said rim extending inward over said washer, and having a continuous serrated conformation at its inner face, each individual tooth thereof being wedge-shaped radially of said nut and presenting a trough widening in a radially inward direction, the sides of said trough indenting the face of said cushion.

4. A lock nut comprising a nut blank having a coaxial cylindrical socket protruding from one face thereof presenting a beveled rim, a cushion washer in said socket, said rim extending inward over said washer, and having a serrated conformation at its inner face with the uninterrupted stiff trough portions thereof indenting the face of said cushion and having a sharp serrated edge biting against said cushion, each trough presenting sharp corners at its inner edge biting into said cushion.

5. A lock nut comprising a nut blank having a coaxial cylindrical socket protruding from one face thereof, presenting a beveled rim, a cushion member fitting into said socket, said rim extending inward and being sharply indented at short uniform intervals, affording a series of connected hollow teeth and presenting a serrated inner face with stiff continuous trough portions indenting said cushion and having relatively sharp edge portions biting against said cushion.

6. A lock nut comprising a nut blank having an upstanding socket, a cushion member in said socket, the rim of said socket being beveled and having a multiplicity of sharply defined wedge-shaped indentations at uniformly spaced intervals and diverging radially inward, said rim having a series of substantially hollow triangular teeth, connected by said indentations, the inner face of said rim having a serrated conformation with the troughs of said conformation severed solely at their innermost edges to form sharp corners thereat, said serrated edge and the sharp corners thereat being embedded in the outer face of the cushion.

7. The method of assembling a lock nut which consists in sharply depressing the inwardly beveled rim of the upstanding socket of a nut blank at a multiplicity of points spaced about the circumference thereof, to form relatively sharp indentations in said rim that define hollow teeth therebetween, and thereby serrating and stiffening said rim and then pressing said inturned indented rim to embed the serrated stiffened inner face thereof into a cushion washer lodged in said socket.

8. The method of assembling a lock nut which consists in sharply depressing the inwardly beveled rim of the upstanding socket of a nut blank, at a multiplicity of points spaced about the circumference thereof to form relatively sharp-edged triangular indentations in said rim while severing the edge thereof to form sharp corners at said severed regions, said indentations defining triangular hollow teeth therebetween at the outer face of the rim, the inner face of the rim becoming serrated, and thereupon pressing said inturned indented rim to embed the serrated inner face thereof as well as the sharp corners thereat into a cushion member lodged in said socket.

9. The method of assembling a lock nut which consists in introducing a cushion washer into a cylindrical socket in the nut blank, forcing radiating sharp tooth impressions into the outer face of the beveled sharp-edged rim of said socket, thereby to produce serrated hollow conformations at the inner face of the beveled rim which

are thereby severed to present sharp corners solely at the inner rim edge of the depressions, and thereupon pressing the inturned rim against the washer to embed the troughs of the serrations, the edges and the sharp corners thereof into the said cushion.

IRVING RICHARDSON.
